FIG. 1.

Isaac L. Edwards
Inventor
Chas J. Williamson
Attorney

UNITED STATES PATENT OFFICE.

ISAAC L. EDWARDS, OF AURORA, ILLINOIS.

RAIL JOINT.

Application filed September 8, 1922. Serial No. 526,985.

To all whom it may concern:

Be it known that I, ISAAC L. EDWARDS, residing at Aurora, Illinois, a citizen of the United States, have invented certain new and useful Improvements in Rail Joints, of which the following is a specification.

The object of my invention is to provide a rail joint which will adequately support the ends of the railroad rails against downward movement under the pressure of the wheels of a passing train and to this end my invention consists in any construction described by or included within the meaning or scope of the appended claims.

15 In the annexed drawings:

Fig. 1 is a perspective view of a rail joint embodying my invention;

Fig. 2 is a cross section;

Fig. 3 is a vertical section on the line 20 3—3 of Fig. 2.

I employ a bed plate, 10, which rests at its ends which are preferably tapering upon the cross ties 11, and upon it rest the ends of adjoining rails, 12. A fish plate, 13, is placed on each side of the rails, each fish plate being substantially L-shape in cross section with a vertical member that lies against the side of the rail extending from the flange to the under side of the head and 25 having a horizontally extending member which overlies the top of the rail flange and projects beyond the edge thereof where it has a downwardly projecting flange or lip, 14, that overhangs and engages the side edge 30 of the flange and reaches to the top of the base plate, 10. At each end the horizontal member of the fish plate is seated in a notch, 15, that is formed by a vertical lug or projection, 16, on the edge of the base plate, 10, and at mid-length said member has a notch, 40 into which extends and fits a vertical lug, 17, on the base plate, 10, and thus fish plate and base plate are interlocked in a way that the fish plate horizontal member acts as a 45 brace between the lugs 16 to stiffen the base plate 10.

The horizontal members of the fish plates are rigidly clamped at mid-length by a clamping device that comprises a horizontal bolt or bar, 18, which passes beneath the base plate, 10, and at one end has an integral finger, 19, which extends upward and thence inward to the vertical member of the fish plate in contact with the upper side of the adjacent horizontal member of such fish plate, and a finger, 20, that has a vertical

shank with a slot, 21, to receive said bolt, 18, and which at the top of the shank extends in contact with the upper side of the adjacent horizontal member of the fish plate towards the vertical member thereof. The finger 20, may be fixed in position by a set screw or bolt, 21, which passes through a threaded hole in the finger shank and engages the side of the bolt or bar, 28, and by 60 a forked wedge, 22, whose legs respectively engage vertical grooves, 23, in the opposite sides of said bolt or bar 18. The bolt or bar, 18, passes through a slot, 24, in a longitudinally extending rib, 25, on the under side 65 of the base plate, 10, said rib thus providing means to prevent the sidewise displacement of the bolt and its clamping fingers and also adding strength to the base plate, 10, directly beneath the joint between the rail 70 ends, a point where great strength is necessary in the base plate.

The clamping finger, 19, by being extended upward alongside of the fish plate constitutes a brace to support the fish plate and 80 rails at the joint between the rails against lateral thrust, and said finger is provided with a downwardly and outwardly curved strut, 26, which helps to take the strains falling upon the finger. 85

Customary bolts and nuts, 27, pass through the fish plates and the rail web and preferably each side member of the fish plate has an extension, 28, with a bolt hole 29, for use should it be necessary. 90

Spikes may be driven into ties through slots or notches, 31, in the base plate near the ends of the horizontal members of the fish plates so that the heads of the spikes may overlap the tops of the horizontal members of the fish plate. 95

What I claim is:

1. A rail joint comprising a base plate, fish plates and a clamp comprising a bar passing beneath the base plate and having 100 fingers that extend upward therefrom and overlap the fish plates on opposite sides of the rail, one of said fingers being integral with the bar and the other made separate therefrom, means comprising a forked member that enters recesses in said bar and engages said separate finger on the outer side. 105

2. A rail joint comprising a base plate, fish plates and a clamp comprising a bar passing beneath the base plate and having 110 fingers that extend upward therefrom and overlap the fish plates on opposite sides of

2
the rail, and a longitudinally extending rib on the under side of the base plate having a slot through which said bar passes.

3. A rail joint comprising a base plate, fish plates having vertical and horizontal members, lugs on the base plate having notches to receive the ends of the fish plates, a lug on the base plate entering a notch in

the fish plate at mid-length thereof, a bar passing beneath the base plate having at opposite ends fish plate engaging fingers and a rib on the bottom of the base plate having an opening through which said bar passes.

In testimony whereof I hereunto affix my signature.

ISAAC L. EDWARDS.
